TELEPHONE BENCH

Arby Hastwell Phibbs, Pulaski, Va.

Application June 16, 1955, Serial No. 36,550

Term of patent 14 years

(Cl. D33—14)

FIG. 1.

FIG. 2.

FIG. 3.

FIG. 4.

I claim:

The ornamental design for a telephone bench, substantially as shown.
